H. R. GREGORY.

AIR DEFLECTOR.

APPLICATION FILED JUNE 26, 1916.

1,221,533.

Patented Apr. 3, 1917.

Harrison R. Inventor:
By John C. Wiggin
His Attorney.

UNITED STATES PATENT OFFICE.

HARRISON R. GREGORY, OF ST. LOUIS, MISSOURI.

AIR-DEFLECTOR.

1,221,533.

Specification of Letters Patent.

Patented Apr. 3, 1917.

Application filed June 26, 1916. Serial No. 105,975.

To all whom it may concern:

Be it known that I, HARRISON R. GREGORY, a citizen of the United States, and resident of St. Louis, Missouri, have invented certain new and useful Improvements in Air-Deflectors, of which the following is a specification containing a full, clear, and exact description, reference being had to the accompanying drawings, forming a part 10 thereof.

The object of my invention is to provide an improved draft deflector for lamp burners, and it consists in the novel construction and arrangement of parts hereinafter 15 described and specifically designated in the claim found at the end of this specification.

The object of my invention is to provide an improved device of the class named, which shall be cheap, highly efficient, simple 20 in construction, and yet be readily detachable from the wick-tube for the purpose of cleaning the parts.

In the drawings:

Figure 1 is a vertical section of a portion 25 of a common oil-lamp and its burner, having my invention applied thereto.

Fig. 2 is a detail vertical section of the burner, having my invention in place thereon, the section being taken on line 2—2 of 30 Fig. 1, and

Fig. 3 is a perspective view of my improved draft-reflector detached.

The numeral 1 designates the body of the deflector, which is in the form of an elongated truncated hollow pyramid of sheet-metal, but having its bottom, top and both 35 of its ends open, for the purpose of permitting currents of air to freely enter during the operation of the device.

At the base of the deflector 1, and extending 40 across each end thereof, is a flat integral horizontal cross-bar 2, which forms the only connection between the opposite inclined sides of the said pyramid.

Between said end cross-bars 2 is a rectangular air-entrance 3, which is of large 45 dimensions, and being unobstructed by the usual supporting-legs, is capable of admitting large quantities of air to the interior 50 of the deflector, from the base thereof, and this, in connection with the freely-open ends of the device, provides ample access for air to the interior of the deflector.

The deflector is secured in position de- 55 tachably upon the wick-tube 4 of the com-

mon lamp-burner 5 by means of the spring-clamps 6, one of which is located beneath and formed integral with the cross-bar 2 at one end of said deflector, and the other one of which spring-clamps 6 is located beneath 60 and formed integral with the cross-bar at the opposite end of said deflector.

Said spring-clamps 6 are U-shaped in plan-view, and the opposite spring side-arms thereof are cut away on their upper 65 edges 7 on an incline, as shown, to make said arms more flexible in their yielding engagement with the opposite sides of said wick-tube from their bases toward their 70 free ends.

The free corners of the sides of the deflector are rounded off at 8, for the purpose of avoiding sharp projections thereat, and to give said corners a more finished appearance. It will thus be seen that the upper 75 ends, or rather, the upper edges of the said spring-clamps 6 are rigidly affixed to the comparatively rigid cross-bars 2, which effectually prevents said clamps from moving toward or from each other, and retains 80 them at all times the proper distance apart, to fit the wick-tube width, and enables the said opposite flexible side-arms of said clamps (with their inclined or tapered portions) to more effectively engage the sides 85 of said wick-tube without any possibility of slipping off of the same.

The operation is as follows:

The deflector is placed beneath the common burner-cap 9, with the said spring-clamps 6 astride the opposite edges of said wick-tube 4 and resting upon the burner-screen plate 10, so that there will be ample 90 unobstructed air passage at the base of the pyramid, and between the inner surface of said burner-cap and the outer surfaces of the side-walls of the deflector, as shown in Fig. 2.

When the wick is lighted the deflector will 100 act very efficiently to not only heat the said wick-tube, but to heat the currents of air as they are drawn upwardly on both the interior and exterior of the deflector walls, and thereby vaporize the oil in said wick-tube, as well as to cause the oxygen of the 105 heated air to unite with the vaporized oil, and produce a more perfect combustion and a larger, and brighter flame above the said burner-cap, as indicated by dotted lines in Fig. 1.

The open ends of the deflector offer no obstruction to the entrance of the air to the interior of the deflector.

The deflector also acts as a very efficient 5 air distributor, as well as a pre-heater of the air before it reaches the flame, and this (as is well known) will produce a more perfect combination of the oxygen with the heated oil-vapor.

10 The following is what I claim as my invention:

An improved air-deflector for lamp-burners, comprising an oblong hollow pyramid of metal, the sides of which are closed, and 15 the top, ends and base of which are open

and unobstructed, the air-entrance at the base being devoid of the usual depending supporting legs thereat; rigid flat cross-bars at the opposite ends of said base; and the opposite U-shaped wick-tube clamps rigidly 20 fixed to the said cross-bars and extending toward the opposite clamps carried by the opposite cross-bar.

In testimony whereof, I have signed my name to this specification, in presence of 25 two subscribing witnesses.

HARRISON R. GREGORY.

Witnesses:

HENRY L. HIGDON,
A. K. STEWART.
